UNITED STATES PATENT OFFICE.

HARRY PLOWMAN, OF LONDON, ENGLAND.

STEAM-GENERATOR OF THE LOCOMOTIVE TYPE.

SPECIFICATION forming part of Letters Patent No. 709,421, dated September 16, 1902.

Application filed April 24, 1902. Serial No. 104,515. (No model.)

To all whom it may concern:

Be it known that I, HARRY PLOWMAN, a subject of the King of Great Britain and Ireland, residing at 122 Kempe road, Kensal Rise, 5 London, W., England, have invented certain new and useful Improvements in Steam-Generators of the Locomotive and other Types, (for which I have made application for Letters Patent in Great Britain, No. 14,275, dated 10 the 12th of July, 1901,) of which the following is a specification.

My invention relates more particularly to steam-generators of the locomotive type, but is also applicable to other types of tubular boiler; and the objects of the invention are to 15 increase the heating-surface and water circulation in such boilers, so as to enable a higher efficiency of steam generation to be attained than in the present type.

20 My invention consists in arranging within the boiler shell or flue a nest of water-tubes which are joined at their ends by headers or connecting-boxes, the one box communicating with the water-space of the boiler and the other one with either the water or steam space, the furnace-gases being caused to traverse the 25 outsides of the tubes, which are so arranged as to provide extra heating-surface within the fire-box.

30 Referring to the accompanying drawings, Figure 1 is a longitudinal section of a locomotive-boiler, showing the method of application of my invention. Figs. 2 and 3 are sections taken on the lines A B and C D, respectively, 35 of Fig. 1. Figs. 4 and 5 are an elevation and a plan, respectively, of the ring-inclosing header and fire-hole, while Figs. 6 and 7 are an elevation and a plan of the header at the fire-box end. Figs. 8 and 9 show the method of 40 applying my invention to the ordinary marine type of Scotch boiler, Fig. 8 being a longitudinal section and Fig. 9 an end view half in section.

The arrows in the figures show the direction 45 of the circulation.

In carrying my invention into effect according to one modification as applied to a locomotive-boiler I provide in the interior of the boiler-shell a longitudinal flue *a*, which extends from the fire-box tube-plate to the smoke-box tube-plate of the boiler and which may be either plain or corrugated. Inside of

this flue I arrange a nest of tubes *b*, which are preferably fitted at an inclination to the axis of the boiler, the slope being upward toward 55 the fire-box end. At the lower or smoke-box end of the tubes a connecting box or header *c* is fitted, having a cover *d* and communicating with the water-space of the boiler through the connection *e*. For the purposes of illustration 60 this connection is shown at the bottom of the boiler. It will, however, be preferable, to avoid any sediment which may collect, to place it more at the side of the boiler. The tubes are carried across the upper portion of the fire-box 65 to the front of the boiler, where they terminate in another header *f*, fitted with a cover *h*, but modified, as shown in Figs. 6 and 7, to admit of its being secured to the ring *i*, which is securely riveted in place between the boiler-shell and the fire-box. The header *f* may communicate with either the steam or water space of the boiler. As shown in Fig. 3, the ring *i* is roughly pear-shaped and incloses both the header *f* and the fire-hole *k*. It is provided at 70 the top with a slot *m*, which, together with a slot *n* in the header *f*, allows the steam generated to escape. The slot *m* also allows the two bolts *o o* to pass through and be screwed to the bridge *p* by the blank end nuts *q q*, thus insuring a tight joint between the two faced surfaces *r* and *s*, Figs. 4 and 6. I sometimes prefer to use a soft-copper ring for making this joint. My object in using the blank end nuts *q q* is to prevent incrustation giving trouble 85 when it is required to break the joint. With this arrangement after breaking the joint just described and removing the blast-pipe *g* I can withdraw the whole nest of water-tubes bodily through the smoke-box door. 90

I provide two hand-holes *tt* in the shell of the boiler, which in the ordinary course of working are closed by blank flanges. These hand-holes allow a box-spanner to be inserted whenever it is necessary to work the nuts *q q*. 95 It will be seen that by this arrangement the front ends of the water-tubes are directly exposed to the heat of the furnace beneath them.

The usual smoke-tubes *u u* are arranged in the space surrounding the central flue *a*, and the hot gases in escaping to the smoke-box and chimney pass through these tubes and along the flue, among the water-tubes which it contains. As shown in Fig. 2, the flue *a* is 100

surrounded on all sides by smoke-tubes *u u*. I sometimes prefer, however, to keep the top of the flue *a* in line with the top of the fire-box, in which case there will be no smoke-tubes immediately above the crown of the flue. By this arrangement owing to the large heating-surface which becomes available and to the continuous circulation of the body of water in streams an increased evaporative efficiency is possible. Brick baffles *z z* are provided with the usual object.

To still further enlarge the heating-surface of the boiler I sometimes place additional water-tubes *v v* immediately above the fire, as shown in Figs. 1, 2, and 3. To insure an efficient circulation through this part of the steam-generating system where the conditions are somewhat more trying, I may provide tubes *w* and *x*, *w* connected to the water-space and *x* to either the water or steam space, circulation taking place in the direction shown by the arrows.

In Figs. 8 and 9 I have shown the application of my invention to an ordinary single-ended marine boiler. I employ two nests of water-tubes 2 and 3, the one set situated in the upper part of the furnace 4, the other set in a special flue 5, riveted to the two tube-plates. This flue, which may be either plain or corrugated, I sometimes slope at the same angle as the tubes, or else I adopt the method of Fig. 1, keeping the flue horizontal and sloping the tubes only. Ordinary smoke-tubes 6 are arranged where space allows around the flue 5. The tubes 2 and 3 are secured at either end to headers 7 and 8, the headers at the back being in their turn secured to rings 9 in the manner already described, and illustrated in Fig. 3. It is, however, to be noted that in the lower back-header the arrangement of Fig. 3 is preferably reversed, so that the slots *m* and *n*, bolts *o*, bridge-piece *p*, &c., are now at the bottom instead of at the top of the header. Suitable connections 10 and 11 are made between the front headers and the water or steam spaces of the boiler and baffles 12 12 are placed in the flue.

Instead of the connection 11 outside the boiler I sometimes shorten the tubes 3, so as to bring the header 7 inside the furnace, a very short connection being then sufficient between the header and the furnace-crown. I may also use an air-blast (not shown in the drawings) for cleaning the tubes, flue, &c.

In the dry-back type of boiler the tubes would cross the combustion-chamber, the header standing in the brickwork flue being

suitably connected to the steam or water space of the boiler.

It will be obvious that with suitable modifications my invention can be readily applied to other types of boilers than those illustrated, such as the double-ended marine boiler, the Cornish boiler, and the Lancashire boiler.

Having now described my invention, what I claim as new, and desire to secure by Letters Patent, is—

1. In a steam-generator of the fire-tube type, a generator-body having a fireplace and a vertically-disposed combustion-chamber at one end, a plurality of fire-tubes extending horizontally from said chamber, a fire-flue located in proximity to said tubes, a plurality of water-tubes extending through the fire-flue and combustion-space, headers connected to said water-tubes at each end, a plurality of water-tubes extending above the grate, headers connecting the ends of said last-named tubes and connections from said headers to the steam or water spaces of the generator, substantially as described.

2. In combination with the fire-flue and combustion-space of a fire-tube generator, of a ring cutting off part of the water-space, a group of water-tubes passing through said flue, a header at each end to which said tubes are connected, and a bridge-piece and bolts with blank end nuts for clamping one of said headers to the ring, substantially as described.

3. The combination with the fire-flue and combustion-space of a fire-tube generator, of a ring cutting off part of the water-space, a group of water-tubes passing through said flue, a header at each end to which said tubes are connected, removable covers for said headers, and a bridge-piece and bolts with blank end nuts for clamping one of said headers to the ring, substantially as described.

4. In a steam-generator of the cylindrical marine type, the combination with the fire-flue and combustion-space, of a group of water-tubes passing through said flue and the upper part of the combustion-space, a second group of water-tubes in proximity to the fire-bed, headers at each end for each group of tubes, and connections from said headers to the steam and water-space of the generator, substantially as described.

In witness whereof I have hereunto set my hand in presence of two witnesses.

HARRY PLOWMAN.

Witnesses:

ALBERT E. PARKER,
FRANCIS J. BIGNELL.
